UNITED STATES PATENT OFFICE

FRANK J. LYNCH, OF HILLSIDE, NEW JERSEY, ASSIGNOR TO PINAUD, INC., OF NEW YORK, N. Y., A CORPORATION OF NEW YORK

DESIGN FOR COLLAPSIBLE TUBE

Application filed March 29, 1930. Serial No. 35,069. Term of patent 14 years.

● *To all whom it may concern:*

Be it known that I, FRANK J. LYNCH, a citizen of the United States, and a resident of Hillside, in the county of Union and State of New Jersey, have invented the new, original, and ornamental Design for a Collapsible Tube, of which the following is a specification:

Reference is had to the accompanying drawings, forming part thereof, wherein the dominant feature is in the arrangement of the rectangular panel and the terraced top having the general appearance of terraces positioned to produce in side elevation the

general outline of a right triangle, and wherein—

Figure 1 is a front view of a collapsible tube showing my new design the rear being identical in appearance with the front;

Figure 2 is a top plan view of the tube shown in Figure 1.

I claim:

The ornamental design for collapsible tube substantially as shown and described.

Signed at Hillside in the county of Union and State of New Jersey this 25th day of March, A. D. 1930.

FRANK J. LYNCH.
